US00D947866S

(12) **United States Design Patent** (10) **Patent No.:** **US D947,866 S**
(45) **Date of Patent:** **** Apr. 5, 2022**

(54) **DISPLAY SCREEN OR PORTION THEREOF
WITH GRAPHICAL USER INTERFACE**

- (71) Applicant: **Apple Inc.**, Cupertino, CA (US)
- (72) Inventors: **Christian Xavier Dalonzo**, San Francisco, CA (US); **Robert Garcia, III**, San Francisco, CA (US); **Chanaka Karunamuni**, San Jose, CA (US)
- (73) Assignee: **Apple Inc.**, Cupertino, CA (US)

(**) Term: **15 Years**

- (21) Appl. No.: **29/738,902**
- (22) Filed: **Jun. 20, 2020**
- (51) LOC (13) Cl. **14-04**
- (52) U.S. Cl. **D14/485**

(58) **Field of Classification Search**

USPC D14/485-495
CPC G06F 3/048; G06F 3/0481; G06F 3/0482; G06F 3/04817; G06F 3/0482; G06F 3/0483; G06F 3/0484; G06F 3/04847; G06F 3/0485; G06F 3/04855; G06F 3/04886; G06Q 30/00; H03J 1/00; H03J 1/0008; H03J 1/0016; H03J 1/0025; H04N 5/00; H04N 5/08; H04N 5/14; H04N 5/222; H04N 5/225; H04N 5/232; H04N 5/445; H04N 5/44543; H04N 5/45; H04N 21/00; H04N 21/234; H04N 21/431; H04N 21/4312; H04N 21/4314; H04N 21/4316; H04N 21/4532; H04N 21/4622; H04N 21/47; H04N 21/478; H04N 21/482; H04N 21/4884; H04N 21/4888; H04N 21/4856; H04N 21/485; H04N 21/6547

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The outer broken lines in the FIGURE show a display screen or portion thereof, and form no part of the claimed design.

**1 Claim, 1 Drawing Sheet
(1 of 1 Drawing Sheet(s) Filed in Color)**
